Mass., a corporation of Massachusetts

Continuation of abandoned application Serial No.
227,841, May 23, 1951. This application August
16, 1952, Serial No. 304,776

7 Claims. (Cl. 139—341)

1

This is a continuation of my copending application Serial No. 227,841, filed May 23, 1951, now abandoned, for a Photoelectrically Controlled Loom Protection.

This invention relates to improvements in loom protection means and it is the general object of the invention to provide for stopping the loom if a shuttle in its flight is not correctly placed to prevent an increase in the illumination of a photoelectric cell.

Loom protections of the mechanical type ordinarily require the shuttle to arrive at the shuttle box toward which it is traveling before indication of timely arrival of the shuttle can be given. In many instances this indication is given by the shuttle binder as it is moved by the shuttle. In such protections, however, it is necessary to delay indication of shuttle arrival until a point so late in the loom cycle that very little time is available to stop the loom.

It is an important object of the present invention to be able to anticipate timely arrival of the shuttle at the shuttle box if the shuttle passes a given point along its travel in time to prevent an increase in the illumination of a photoelectric cell. If the shuttle is late the increase in illumination occurs and electric circuit means controlled by the cell effects prompt loom stoppage.

It is another object of the invention to locate photoelectric cell and lamp elements on opposite sides of the shuttle path and provide means by which the lamp element can project a beam of light across the shuttle path to increase illumination of the cell element. The beam of light is located at a critical point in the path of the shuttle and if the latter is able to intercept the beam of light there will be no change in the illumination of the cell and the loom will continue to run, but if the shuttle is not able to intercept the beam of light loom stoppage will follow.

It is another object of the invention to provide loom stopping electric means including two parallel circuits for controlling a master relay, one of these circuits being opened periodically by a loom controlled switch at the time the shuttle will be at said critical point if running on time. The switch when opening this circuit will close a contact to cause an increase in the illumination of the lamp for the photoelectric cell, thereby enabling a single switch to perform the dual function of opening a normally closed control circuit and also effecting increased illumination for a lamp.

It is a further object of the invention to provide each of the aforesaid parallel circuits with

2

switches both of which are normally closed, one of said switches being opened periodically as already mentioned, and the other being opened incident to action of a control circuit in the event that illumination of a photoelectric cell is increased.

In order that the invention may be clearly understood reference is made to the accompanying drawings which illustrate by way of example the embodiments of the invention and in which:

Fig. 1 is a front elevation of a loom, parts being broken away, having the invention applied thereto,

Fig. 2 is an enlarged vertical section on line 2—2, Fig. 1, showing the lay in full lines in the position which it occupies while the shuttle is in flight through the warp shed and in broken lines when the lay is at front center,

Fig. 3 is an enlarged detailed end elevation looking in the direction of arrow 3, Fig. 1,

Fig. 4 is a plan view of the shuttle and bobbin therein such as may be used with the invention, and

Fig. 5 is a diagrammatic view of a form of electric circuit which can be utilized to carry the invention into effect.

Referring to Fig. 1, the loom has right and left loom-sides 1 and 2, respectively, which support a rocker shaft 3 for the right and left lay swords 4 and 5, respectively, which support the lay designated generally at 6. In the present instance the lay has a single shuttle box R at the right end thereof and a gang L of two shuttle box cells 7 and 8 at the left end thereof. The loom has two means to lay weft in a warp shed, shown here as shuttles, one of which S1 is shown in the loom shuttle box R and the other of which S2 is shown at the left end of the loom in the lower shuttle box cell 8.

The lay swings backwardly and forwardly in the loom in usual manner by power imparted to it from a top shaft 10 through connectors one of which is shown at 11 in Fig. 2. The top shaft has a gear 12 secured thereto meshing with a gear 13 of twice its size secured to the bottom shaft 14. The latter shaft has right and left picking arms 15 and 16 for cooperation with picking cams 17 and 18, respectively, operatively connected to picker sticks P1 and P2, respectively.

The picker sticks operate one at a time and usually during the backward stroke of the lay when it is at or near its top center position, that is, approximately midway between its extreme front and back positions. Each picker stick when operating will propel the shuttle aligned with it

from one end of the loom to the other end, causing it to pass through a warp shed designated generally at W, see Fig. 2, comprising upper and lower planes or groups of warp threads 20 and 21. These threads pass through a reed 22 the lower end of which is positioned by the lay beam member 23 and the upper end of which is positioned by a hand rail member 24. The latter is supported by arms 25 one of which is shown in Fig. 2 extending upwardly from the lay structure 6. 10 The lay beam has a shuttle race 26 under the hand rail and along which the shuttles travel when in flight between shuttle box structures R and L.

At the time of shuttle picking the lay will be moving rearwardly, or to the right as viewed in Fig. 2, and will ordinarily reach its back center position while the shuttle is in flight through the warp shed. The lay will then start to move forwardly as the shuttle continues on its flight through the warp shed. If for any reason the shuttle should be traveling slower than usual, or should be stopped in the warp shed, it will be necessary to effect prompt stoppage of the loom in order to prevent the reed 22 from pushing the shuttle forwardly through the warp shed and breaking some of the warp threads of the top and bottom thread groups 20 and 21. It is the general purpose of the present invention to effect this stoppage of the loom should the shuttle fail to reach a given point in its travel along the lay at a given time in the cycle of the loom.

The shuttles may be as shown in Fig. 4 which shows shuttle 28 and its bobbin 27. Any other type of shuttle can be used, however, so long as it has opaque parts, such as ends 28 and 29, capable of interrupting a beam of light.

The matter thus far described may be constructed and operated in the usual manner.

The loom is driven by a motor 30 which as shown herein is provided with a pinion 31 meshing with a motor gear 32 fixed to the top shaft 13. The motor is of the so-called stop and start type and whenever the motor is in operation the loom will be running and whenever the motor is stopped the loom will stop with it. The motor is controlled by electrical devices which need not be described in detail herein but which are contained in a panel or box 33, see Fig. 5, which in turn is controlled by a master relay 34.

The relay controls a master switch MS, see Fig. 5, having an armature or switch blade 35 and a contact 36 therefor. When the relay 34 is energized the blade 35 is in engagement with the contact 36 and wires 37 and 38 leading from the switch MS to the panel 33 are electrically connected and maintain the condition for continued running of the motor. If the relay 34 becomes deenergized spring 39 will open switch MS and the wires 37 and 38 will be electrically disconnected, whereupon the equipment within the panel 33 will effect very prompt stoppage of the motor and loom. The master relay 34 and its switch MS, and the equipment controlled by the switch may be considered to be loom governing means controlling motor and loom operation.

Loom stoppage may be effected by any of the known electrically operating means for this purpose, such as by a magnetic brake, or by application of a so-called plugging current which will stop the motor almost instantly. The motor 30 will ordinarily be operated by a three-phase alternating current and the plugging may be effected by direct current. I do not wish to be limited to any particular means for stopping the motor and

it will be sufficient for the purposes of the invention if electric means operates to stop the motor upon deenergization of the master relay 34.

Energization of the master relay 34 is controlled by two switches one of which is a loom controlled timer switch designated at TS and the other of which is a shuttle controlled switch designated at SS. The timer switch includes a contact arm 43 normally held against contact 41 by a spring 42 but moved away from the contact 41 periodically by point 48 of a cam 44. The cam 44 is secured to a shaft 45, see Fig. 3, mounted for rotation in a stationary stand 46 which is mounted on the left hand loom-side 2 as viewed in Fig. 1. The stand 46 supports the contact arm 43 and also the contact 41.

A sprocket wheel 43 secured to the top shaft 10 is connected by a chain 48 to another sprocket wheel 59 of the same size as sprocket 43 secured to the shaft 45. The cam 44 therefore completes a rotation each pick or beat of the loom and the cam point 48 will open the timer switch TS at regularly recurring intervals each pick of the loom when the shuttle should be at a given point in the path of its travel along the lay. I do not wish to be limited to the particular type of timer switch shown in Fig. 3, and it will be sufficient if the timer switch is such that it is normally closed but opens periodically.

The master relay 34 is in an electric circuit including a transformer 53, wire 56, wires 57 and 58, contact 41, arm 43 and wire 59, back to the transformer. During the greater part of the cycle of the loom this circuit will be closed and the master relay will be maintained energized by current flowing through contact 41, but as already mentioned this circuit will be opened periodically and unless relay 34 is energized by closure of the switch SS at such times the relay will become deenergized and effect loom stoppage.

The loom is provided with means for directing a beam 60 of light across the shuttle race 26 and the path of the shuttle, and as shown herein through the warp shed. This beam of light may be provided by an electric lamp element 61 having a filament 62 and carried by a small stand 63 secured to the hand rail. The hand rail has a hole 64 therethrough below the lamp.

The lay beam 23 is provided with a hole 65 aligned with the hole 64, and a photoelectric cell unit or element 66 supported on the under side of the lay beam is in the path of the beam of light originating with the filament 62 and passing downwardly through the hole 64, through the upper and lower sheets 20 and 21 of warp threads, through shuttle race 26, and through the hole 65 in the lay beam.

One side of lamp 61 is connected by wire 70 to one side of the transformer and the other side of the lamp is connected by wire 71 to a resistance R which is connected to the transformer. A contact 72 is connected to wire 71 and is positioned to be engaged by switch arm 43 when the latter is moved away from its normal position shown in full lines, Fig. 5, to a second position thereof shown in dotted lines, Fig. 5, by cam point 43. During the greater part of the cycle of the loom electric current will flow through resistance R in series with lamp 61 but will be too weak to illuminate the lamp. When switch arm 43 engages contact 72 the resistance will be short circuited and the current then flowing through the lamp will be large enough to increase the illumination of cell 66. The switch arm 43, the cam point 43 which moves it against contact 72 and the trans-

former 55 are periodically acting means to increase the luminosity of the lamp 61.

Two wires 80 and 81 supplying preferably direct current are connected by resistances R1, R2 and R3 which are in series as shown in Fig. 5. Adjustable tap 82 is slidable along the resistance R2 and is connected to a resistance R4 which in turn is connected to a junction point 83. An electronic tube E preferably of the high vacuum type has a cathode 84, a control grid 85, and a plate 86. The plate is connected by wire 87 to a control relay 88 which when energized opens normally closed switch SS. The other side of the relay 88 is connected to the positively charged wire 80. The photoelectric tube 66 has an anode 90 connected by wire 91 to wire 80 and has a cathode 92 connected by wire 93 to junction 83.

Normally, the control relay 88 is deenergized and its armature contact arm 95 engages contact 96 so that switch SS is closed. This condition exists because junction 83 and grid 85 are at a relatively low voltage due to the fact that cell 66 is not illuminated. When cam point 43 causes arm 40 to engage contact 72 the resistance R is short circuited and lamp 61 is bright enough to effect a large increase into the illumination of cell 66 and the latter is able to transmit more electric current and the voltage of junction 83 and grid 85 is raised. The grid, being less negative than previously, permits enough current to flow through tube E to energize control relay 88, and switch SS will be opened. This latter condition exists if the illumination of cell 66 is increased, and since switch TS is open at this time the master relay will become deenergized and the loom will stop. The photoelectric cell 66, the tube E, the control relay 88 and its contact arm 95, and the electric connections for these parts, may be considered to be electronic circuit means controlling the loom governing means.

Whether or not the periodic increase in brightness of lamp 61 results in increased illumination of the cell 66 will depend upon the position of the shuttle. If the latter is in the dotted line position shown in Fig. 5, that is, able to cause a shadow on cell 66 and prevent an increase in its illumination, control relay 88 will remain unchanged and switch SS will remain closed to keep master relay 34 energized to maintain loom operation. This will happen if the shuttle is running on time and reaches the beam of light at the given time in the loom cycle when switch TS opens. If, on the other hand, the shuttle is running late or slow and is in the full line position, Fig. 5, when switch TS is opened, there will be an increase in illumination of cell 66 with resultant energization of control relay 88 and opening of switch SS, and the loom will be stopped.

When the shuttle is on time, therefore, switch SS remains closed to maintain closure of switch MS, but if the shuttle is late both switches TS and SS open practically simultaneously and switch MS opens to stop the loom.

From the foregoing it will be seen that an increase in the illumination of a photoelectric cell 66 is relied upon to stop the loom if the shuttle is running slow, but if the shuttle is on time it casts a shadow on the cell to prevent an increase in its illumination. The single switch arm 40 serves the dual purpose of breaking one of the parallel circuits for the master relay and at the same time effecting a change in the amount of

light given off by the lamp element 61. If the shuttle interrupts the beam of light when the latter is bright the loom will continue to run, but if the beam is able to increase the light falling on the photoelectric cell before the shuttle arrives the loom will stop. Both switches TS and SS will normally be closed, and if switch SS remains closed while switch TS is open the loom will continue running. The master relay is controlled by two parallel electric circuits one of which includes wire 58, contact 41 and contact arm 40 and is opened periodically by loom operated cam point 43 and the other of which includes contact arm 95 and contact 96 and is opened due to an increase in the illumination of the photoelectric cell 66.

Having now particularly described and ascertained the nature of the invention and in what manner the same is to be performed, what is claimed is:

1. In protection means for a loom operating with a shuttle which when running on time passes a given point along the path thereof at a given time in the loom cycle, loom governing means capable of effecting continued loom operation or stoppage of the loom, electronic circuit means controlling the governing means including a photoelectric cell, periodically acting means tending to increase the illumination of said photoelectric cell at said time but prevented from doing so by the shuttle if the latter is running on time, said electronic circuit means being effective upon an increase in the illumination of said photoelectric cell to cause the governing means to stop the loom.

2. In protection means for a loom operating with a shuttle which when running on time passes a given point along the path thereof at a given time in the loom cycle, loom governing means capable of effecting continued loom operation or stoppage of the loom, electronic circuit means controlling the governing means including a photoelectric cell, and a light source means acting periodically at said time in the loom cycle to direct a beam of light across said path at said point to increase the illumination of said cell to cause the governing means to stop the loom but prevented from doing so if the shuttle is running on time.

3. In protection means for a loom operating with a shuttle which when running on time passes a given point along the path thereof in a warp shed at a given time in the loom cycle, loom governing means capable of effecting continued loom operation or stoppage of the loom, electronic circuit means controlling the governing means including a photoelectric cell, periodically acting means tending to direct a beam of light through the warp shed to increase the illumination of said photoelectric cell at said time to stop the loom but prevented from doing so if the shuttle is running on time in the warp shed.

4. In protection means for a loom having a shuttle which moves along a path incident to loom operation, a photoelectric cell, loom governing means capable of effecting continued loom operation or loom stoppage, electronic circuit means including said photoelectric cell controlling said governing means and effective upon an increase in the illumination of said cell at a given time in the loom cycle to cause the governing means to stop the loom and effective if the illumination of said cell at said time remains unchanged to cause said governing means to effect

continued loom operation, and light source means tending periodically at said time in the loom cycle at a given point along the path of the shuttle to direct a beam of light onto the photoelectric cell to increase the illumination thereof, the shuttle if running on time arriving at said given point at said time to prevent the light source means from increasing the illumination of the cell, said light source means in the event that the shuttle fails to reach said point at said time effecting an increase in the illumination of the photoelectric cell to effect loom stoppage by said governing means.

5. In protection means for a loom dependent for continued operation upon unchanged illumination of a photoelectric cell at a given time in the loom cycle, means effective to stop the loom if the illumination of the cell is changed at said time, means tending at said time to effect a change in the illumination of said cell, and a shuttle effective if running on time to prevent said last named means from increasing the illumination of said cell.

6. In protection means for a loom dependent for continued operation upon energization of a relay, electric means including an electric switch normally in one position to effect energization of the relay, periodically acting means to move said switch to a second position to effect de-energization of the relay, a photoelectric cell, 30 electronic circuit means controlled by the cell effective if the illumination of the cell is unchanged when said switch is in said second position to maintain the relay energized, the electronic circuit means causing the relay to become deenergized if the illumination of said cell is changed when the switch is in said second position, an electric lamp tending when il-

luminated to change the illumination of the cell, means controlled by said switch effective when the latter is in said second position thereof to illuminate said lamp, and a shuttle effective if running on time to prevent said lamp from illuminating said cell while said switch is in said second position thereof.

7. In protection means for a loom operating with a shuttle moving along a path thereof and continued operation of the loom being dependent upon energization of a relay, two parallel electric circuit means closure of either of which effects energization of the relay, a switch for one of said circuit means normally closed to effect energization of the relay by said one circuit means, means periodically opening said switch to open said one circuit means, a second switch for the other of said parallel circuit means normally closed to effect energization of the relay when the first switch is open, photoelectric circuit means controlling the second switch including a photoelectric cell effective upon an increase of illumination of said cell to open said second switch, and means tending to increase the illumination of said cell when the first named switch is open by projecting a beam of light across said path but prevented from increasing illumination of the cell if the shuttle is in said beam of light.
